H. W. DYER

EXIT DOOR LOCK

Filed April 30, 1923

Harry W. Dyer INVENTOR.

BY

W. H. Langbridge ATTORNEY.

UNITED STATES PATENT OFFICE.

HARRY W. DYER, OF NEW YORK, N. Y.

EXIT-DOOR LOCK.

Application filed April 30, 1923. Serial No. 635,571.

To all whom it may concern:

Be it known that I, HARRY W. DYER, a citizen of the United States, and resident of New York, in the county of New York and State of New York, have invented certain new and useful Improvements in Exit-Door Locks, of which the following is a specification.

This invention relates to door locks and particularly to door locks of the panic bolt type and is intended for application on double doors. The objects of the invention are to provide means whereby in a double door pressure against either door on the inside will result in unlatching the door and permit it to open; these results are obtained without interfering with the normal opening and closing of either door. These and other objects of the invention will be more fully understood from the following specification and the accompanying drawings, in which, Fig. 1, is a front view of a lock operating mechanism applied to one of the doors, Fig. 2, is a side view of Fig. 1; Fig. 3 is a lock operating mechanism applied to the other door, Figs. 4 and 5 are details showing the construction used in Fig. 3, Fig. 6 shows the operative relation between the mechanisms on each door, Fig. 7 shows the invention applied to a double door and Fig. 8 shows the construction of a latching mechanism that may be used at the top of the door. Similar reference characters are used for similar parts throughout the various illustrations.

This invention is shown applied to what is known as a panic bolt lock, that is to a type having a horizontal bar on the inside which, when pressure is applied thereto unlatches the lock and permits the door to open outwards. Public buildings are usually supplied with double doors and to one of these doors the locking mechanism is applied which latches at the top and bottom, this is sometimes called the stationary door. The other door latches to the stationary door having a knob or latch on the outside for releasing purposes and a similar arrangement may be provided on the inside. It is often desirable that the panic bolt type of release be applied to both doors so that pressure on either door will unlatch the stationary door and permit both doors to open outwards. The present invention is designed to accomplish this purpose.

The lock operating mechanism on the sta-

tionary door is provided with a releasing arm located close to the door opening and a releasing arm is provided on the other door close to the opening but clear of the same so that either door may be opened or closed by the knob or latch without conflicting with each other. The first operation of the releasing arm on the moving door is to move it horizontally into engagement with the releasing arm of the stationary door and the continued movement moves the latter arm into the unlatching position. When unlatched both doors open together and releasing pressure on the panic bolt restores the releasing arms to their normal position within the clearance of the door opening.

Referring to the drawings, 11 indicates the closing edge of the stationary door and 12 is the closing edge of the moving door. The bearing plate 13 is secured to 11 and has the bearing lugs 14 formed integral therewith. These lugs support a shaft 15 to which the releasing dog 16 is secured, also the releasing arm 18 which develops into the extension 22 adjacent the opening 11. Pivoted on shaft 15 by jaw 19 is the horizontal panic bolt 21 as shown. This bolt is loosely pivoted on shaft 15 but has an extension or pad indicated at 20 which engages 16 causing the latter to rotate as this bolt is pressed inward, while the dog is free to rotate independently by pressure applied to the releasing arm 18. The end of dog 16 engages a locking mechanism indicated at 17, Fig. 2 and may be constructed as shown in my co-pending applications 565,156 or 572,775. It is intended that this dog may be constructed operating a cam or lever to adapt it to the type of locking mechanism used. As shown in the drawing the upward movement of 17 releases the lock.

The releasing arm on the moving door is indicated at 24 and is supported by shaft 25 moving in sleeve 26 which is supported by the bearing lugs 27 in the bracket 28. On sleeve 26 the panic bolt 29 is pivoted and is held in the released position by the coil spring 36. The sleeve 26 is provided with a cam slot shown at 31, Fig. 5 and shaft 25 is provided with a pin 32, Fig. 3 arranged to move freely in slot 31. The end of this pin projects above sleeve 26 and engages a longitudinal slot of key-way 33, Fig. 3, in the bearing of 29. In assembling, the shaft 25 is inserted in sleeve 26 and then pin 32 is inserted through the slot and

secured to 25. The sleeve is now inserted in the bearing lugs 27 and the bearing of bolt 29, being turned so that pin 32 aligns with the slot opening 34 as shown in Fig. 4. 5 After inserting the sleeve is turned around until the pin is vertical, this aligns the sleeve in position for the screws 35 which securely fasten it rigid with the lugs 27.

When the bolt 29 is under pressure it tends to rotate on the sleeve 26 and engaging pin 32 through slot 33 tends to rotate this pin also. This pin is guided by the fixed slot 31 and the movement of shaft 25 is thus directed by the shape of this slot. 10 This slot, it will be noted has an inclined portion which forces the shaft 25 outwards towards the other door so that it extends beyond the opening 12 carrying with it the arm 24 which is thus moved into the plane 15 of the releasing arm 22. The under surface of arm 24 is rounded or spherical shaped as indicated at 23, Fig. 1 so that when it engages 22 it will slide over the latter easily. It will be noted from the shape of the slot 20 that continued movement of arm 29 will rotate shaft 25 thus applying an inward pressure to the releasing arm 22 and thereby unlatching the door. The relation of the arm 24 to arm 22 is shown in Fig. 6 when 25 in the releasing position. The spring 36 in restoring the bolt 29 moves pin 32 backwards through the slot and brings arm 24 into its normal position. Attention is called to the fact that the arm 24 is longer than 30 arm 22, the increased movement thus secured at the end of this arm enables it to release the lock with less angular movement of shaft 25 than is required of shaft 15 so that the lock will release with approximately 35 the same inward movement of bolt 29 as of bolt 21.

It will be noted from Fig. 6 that in applying this mechanism very little change is required in standard mechanisms of this kind, the construction is compact, simple, 40 easy to assemble and not likely to get out of order. The clearances are shown in Fig. 7 in which 40 indicates the stationary door and 41 is the moving door. This door opens 45 in the clearance α by a knob or latch without conflicting with the fixed door.

The latching mechanism at the top of the door may be operated as indicated by Figs. 1, 2 and 8, in which 45 is an up and down rod operated by 16. This rod enters a mechanism 46 and has a cylindrical end 47 as shown which is provided with a semi-circular opening to engage the circular end of lever 48 pivoted at 49. The opposite end 50 of this lever engages a similar opening in plunger 50 of the latch 51. It will be noted that an upward movement of rod 45 will cause a downward movement of the latch and vice versa; so that the weight of rod 45 tends to hold the latch in the engaging posi-

tion. This type of construction is found to be simple, very effective and comparatively inexpensive.

This invention has been described as applied to double doors which is its most 70 common use at the present time, it is apparent however that the principles of the invention may have a much wider application and I do not wish my invention to be regarded as a construction solely for use 75 on double doors.

Having thus described my invention, I claim:

1. In a door lock of the class described for double doors, a locking mechanism on one 80 door, a releasing mechanism on the other door, said mechanisms placed on said doors so as not to project beyond the abutting edges thereof and means for moving the releasing mechanism to engage said locking mechanism whereby said locking mechanism is operated to release the door to which it is attached.

2. In a door lock of the class described for double doors, a locking mechanism on one 90 door, a releasing mechanism on the other door, these mechanisms placed on said doors so as not to project beyond the abutting edges thereof, means for imparting a preliminary movement to the releasing mechanism bringing it into the plane of the locking mechanism and means for releasing the locking mechanism.

3. In a door lock of the class described for double doors, a locking mechanism having a 100 shaft with an arm on one door, a releasing mechanism having a shaft with a releasing arm on the other door, these mechanisms placed on said doors so as not to project beyond the abutting edges thereof, means for imparting a side movement to the releasing arm bringing it into engagement with the locking mechanism and means for operating the locking mechanism by said arm.

4. In a door lock of the class described for double doors, a locking mechanism with a releasing member on one door, a releasing mechanism with a releasing arm on the other door, these mechanisms placed on said doors so as not to project beyond the abutting edges thereof and means for operating said locking mechanism by a combined side and rotary movement of said releasing arm.

5. In a door lock of the class described for double doors, a locking mechanism having a 110 rotary releasing member on one door, a releasing mechanism having a rotating arm on the other door, these mechanisms placed on said doors so as not to project beyond the abutting edges thereof and means for imparting a rotary motion to said releasing member from said rotating arm.

6. In a door lock of the class described, the combination of a bracket secured to a 120 door and supporting a horizontal releasing

bolt, a releasing arm pivoted to said bracket and means for imparting a side and rotary movement to said arm by the movement of said bolt.

5 7. In a door lock of the class described, the combination of a bracket secured to a door and supporting a releasing bolt, a releasing member pivoted to said door, means for imparting a movement to said pivot 10 moving said arm beyond the edge of said door and means for rotating said arm on said pivot by the movement of said releasing bolt.

8. In a door lock of the class described, 15 the combination of a bracket secured to a door, a sleeve with a cam formation rigidly secured to said bracket, an operating bolt pivoted on said sleeve, a shaft pivoted in said sleeve and having a releasing lever associated therewith, said shaft operatively connected with said sleeve and said bolt.

9. In a door lock of the class described, the combination of a locking mechanism having a releasing arm working on a pivot, a releasing mechanism having a releasing lever working on a pivot, means for bringing said releasing arm into engagement with said re-

leasing lever, said releasing lever being longer than said releasing arm and means for operating said releasing lever through 30 its pivot.

10. In a door lock of the class described, the combination of a locking mechanism, a vertical rod associated with said mechanism, a latch and plunger at the top of said door, a pivoted lever connecting said vertical rod with said plunger whereby their direction of movement is reversed, said lever having rounded ends and engaging rounded apertures in said rod and plunger. 40

11. In a door lock of the class described for double doors, a mechanism for locking one door at top and bottom, a mechanism on the other door for releasing said locking mechanism, said releasing mechanism comprising a horizontal releasing bar, a device normally standing within the plane of said door and operated by said bar to extend beyond the plane of said door and release said locking mechanism. 45

Signed at New York in the county of New York and State of New York this 8th day of March, A. D. 1923.

HARRY W. DYER.
